UNITED STATES PATENT OFFICE.

WILLIAM P. WITHEROW, OF PITTSBURGH, PENNSYLVANIA, ASSIGNOR, BY MESNE ASSIGNMENTS, TO COLONIAL TRUST COMPANY, TRUSTEE, OF PITTSBURGH, PENNSYLVANIA, A CORPORATION OF PENNSYLVANIA.

METHOD OF MAKING RING-GEAR BLANKS.

Application filed August 1, 1923. Serial No. 655,062.

The present invention relates broadly to metal working, and more particularly to the art of die-rolling and forging as applicable to the production of gears, such, for example, as ring gears of the character used in the automotive industry, although the utility of the invention is not limited in this respect, it being also highly desirable in the making of chain.

At the present time considerable attention is being paid to the manufacture of ring gears in an effort to produce stronger gears at a reduced cost and in larger numbers, as required by the increasing demand for automobiles. One of the important problems in this art lies in the production of a blank having a proper disposition of fibres, so that the fibres in the finished blank will extend in the required direction. Preferably such fibres should extend either radially or circumferentially, but in any case, irrespective of the direction of extension of the fibres, it is desirable that they be as nearly uniformly disposed throughout the entire blank as possible.

In accordance with the present invention, there is provided an improved method of making ring gear blanks in quantity and of such material that a very desirable arrangement of fibres is insured.

In the accompanying drawings there are shown for purposes of illustration only certain preferred embodiments of the present invention, it being understood that the drawings do not define the limits of my invention, as changes may obviously be made in the construction disclosed therein without departing from the spirit of the invention or scope of my broader claims.

In the drawings,—

Figure 1 is a top plan view illustrating a portion of a connected series of loop-shaped blanks as formed by die-rolling;

Figure 2 is a view similar to Figure 1, illustrating a preferred manner of separating the individual blanks;

Figure 3 is a top plan view illustrating a modified method of separating the blanks;

Figure 4 is a view of a blank such as illustrated in Figure 2, which has been worked to substantially ring shape;

Figure 5 is a top plan view of a blank which has been subjected to a forging operation;

Figure 6 is a similar view of a blank with the flash removed therefrom;

Figure 7 is a transverse sectional view through the blank illustrated in Figure 6;

Figure 8 is a side elevation illustrating a modified embodiment of the invention.

In accordance with the present invention a leader or billet of suitable shape having a sufficient cross-sectional area to provide blanks having the necessary amount of metal, is passed through die-rolls to produce a connected series of loop-shaped blanks 2, as clearly shown in Fig. 1. These loop-shaped blanks are preferably spaced one from the other and connected by means of gates 3. By so shaping the die-rolls that gates between the blanks are formed, it is possible to reduce the thickness of the flash at all points around the blanks to a minimum and thereby facilitate the subsequent trimming of the blanks.

After a connected series of blanks of this character has been produced, they are preferably subjected to a shearing operation which entirely removes the flash or gate from one end of each of the blanks and from the inside thereof, thereby providing the full gate on the opposite end, as shown in Figure 2. This gate constitutes a tong hold enabling an operative to easily manipulate the blank during all of the operations which are performed thereon.

In some cases it may be desired to separate the blanks in pairs, as illustrated in Fig. 3 whereby one blank may serve as a tong hold for the other during subsequent operations.

It will be apparent that by the die-rolling process there are provided blanks in which the fibers in the side of the blanks extend substantially lengthwise thereof. In the ends of the blanks, however, the fibers, while deformed somewhat due to the die-rolling operation, may be considered as extending partly around the end portions and partly lengthwise of these end portions. Such a disposition of fibers in a finished blank, while giving all of the strength required, would be objectionable due to the non-uniformity. In order to overcome this objection, the blanks are preferably rolled so as to provide an excess of stock in each of the ends 4 of the blanks. This excess of stock

insures a greater amount of working on the end portions of the blank than on the other portions, and thereby very effectively breaks up the fiber arrangement described and produces a blank in which the fiber arrangement is substantially uniform, extending around the blanks.

The individual blanks illustrated in Fig. 2 may be worked to shape by subjecting them to the action of a forging hammer, or by rolling. If a forging hammer is used, the blanks in the same heat may be shaped by dies to the form shown in Fig. 4, and then pressed by the same hammer for imparting the desired cross-sectional shape, as shown in Fig. 5. This provides a bevel face 6 on which teeth may be formed, and an inwardly projecting flange 7 for the attachment of the gear. The flash 8 produced by this operation is then removed in any desired manner to form a clean blank, as indicated in Fig. 6, adapted to have the teeth cut therein. Due to the excess of metal in the ends of the blank, these portions are subjected to a greater amount of work, thereby effectively breaking up the fiber arrangement. This insures a finished gear in which the fiber arrangement is substantially uniform.

In actual practice it has been found highly desirable in some instances to produce a connected series of blanks of the character described, and then ship the same to customers, by whom the blanks are made into finished gears. In other cases the series may be sheared or separated, as indicated in Fig. 2, and similarly handled. In this manner the die-rolling may be accomplished under given specifications at a central point and the blanks then shipped as articles of manufacture to other points for completion.

It will be understood that in accordance with this invention it is possible to produce blanks in rapid succession with a substantially uniform distribution of stock in successive blanks. This distribution of the stock facilitates the subsequent operations on the blanks and insures disposing of the stock in such a manner that very efficient results are obtained. In some cases the cross sectional area throughout the periphery of the blanks may be uniform or otherwise varied as may be deemed necessary.

Preferably the leader employed has a width substantially equal to the maximum width of a rolled blank, and a thickness substantially equal to the maximum thickness of the rolled blank. This facilitates the rolling operation and insures greater uniformity on successive blanks.

I have also found that the first steps of the method herein described may be advantageously used in the manufacture of chains. In such cases, a connected series of blanks as shown in Figure 1, but preferably with

a uniform cross sectional area throughout each blank, may be trimmed to provide individual loop-shaped rings. Each pair of rings may thereafter be joined, as is customary in the art and as illustrated in Figure 8, by welding a connecting link 9 therebetween. This decreases the welding steps by one-half, and produces a chain at a much reduced cost.

Further advantages of the invention arise from the production of a blank in which the fibers are substantially uniformly disposed throughout the entire body thereof, whereby a finished blank having substantially uniform strength is insured.

I claim:

1. In the method of manufacturing ring gear blanks, the steps consisting in die-rolling a leader to produce a series of blanks separated by connecting gates, separating the connected blanks to provide a tong hold for the separated blanks, and then working the blanks to shape.

2. The method of making ring blanks which comprises rolling a leader to produce a connected series of loop-like blanks, each having side portions and curved connecting end portions gradually merging into the side portions and having an interior web, removing the interior web, and reworking the loop-like blanks to substantially circular form.

3. The method of making ring blanks which comprises rolling a leader to produce a series of loop-like blanks, each having side portions and curved connecting end portions gradually merging into the side portions, the blanks being separated from one another by a gating and having an interior web, removing the web and reshaping the loop-like blanks.

4. The method of making ring blanks which comprises rolling a leader to produce a series of loop-like blanks, each having side portions and curved connecting end portions gradually merging into the side portions, said end portions having an excess of stock over the side portions, the blanks having an interior web, removing the web and reworking the blanks.

5. The method of making ring blanks which comprises rolling a leader to produce a connected series of loop-like blanks, each having side portions and curved connecting end portions gradually merging into the side portions, the blanks being spaced apart and connected by a gating, the string of blanks having flash on diametrically opposite sides of the string adjacent the gating and having substantially no flash along the side portions of the blanks, and reworking the blanks.

6. The method of making ring blanks which comprises rolling a leader to produce a connected series of loop-like blanks, each having side portions and curved connecting

end portions gradually merging into the side portions, the blanks being spaced apart and connected by a gating, the string of blanks having flash on diametrically opposite sides of the string adjacent the gating and having substantially no flash along the side portions of the blanks, and reworking the blanks, the blanks being separated in such manner that a gating is connected to a blank for use as a tong-hold during reworking.

7. The method of making ring blanks which comprises die rolling a leader to produce a connected series of loop-like blanks each having a pair of side portions of substantially uniform cross-sectional shape lying side by side and having an interior web, the side portions being connected by generally semi-circular end portions, the end por-

tions having substantially the same cross-sectional shape as the side portions and gradually merging into such side portions, and reworking the loop-like blanks to substantially circular form.

8. The method of making ring blanks which comprises rolling a leader to produce a connected series of loop-like blanks, each having side portions and curved connecting end portions merging into the side portions, the blanks being spaced apart and connected by a gating, the string of blanks having flash adjacent the gating and having substantially no flash along the side portions of the blanks, and reworking the blanks.

In testimony whereof I have hereunto set my hand.

WILLIAM P. WITHEROW.
